6 Claims. (Cl. 261—84)

The present invention relates to a device for producing a combustible mixture or charge for piston type internal combustion engines and particularly for aircraft engines provided with superchargers.

It is an object of this invention to provide a device of the described character which ensures perfect atomization of the fuel, is easily adjustable, operates reliably in all flight positions and is simple and reliable in service.

At present, piston-type internal combustion engines generally use either carburetors or injection pumps. Both these fuel feeding systems have numerous operating disadvantages, such as, imperfect atomization of the fuel, inferior acceleration and starting of the engines, possibility of icing and, in aircraft engines, interruption of the feeding of fuel when performing acrobatics. There are further drawbacks relating to manufacturing costs and difficulties during manufacture, and to the complexity and lack of sturdiness of the existing systems.

In accordance with this invention a rotating body is provided with a number of substantially radial channels terminating in nozzles and acting as a centrifugal pump. Such body may be supported by the shaft of the rotor of the engine supercharger. The fuel is atomized either by the nozzles alone or by pan shaped discs or by a combination of nozzles and discs. Thus perfect and uniform atomizing of the fuel within a wide range is achieved for any required condition of the engine. The output of the engine is increased and the performance is more economical and reliable, as a more uniform distribution of the combustion mixture into the respective engine cylinders is achieved.

Since the atomization of the fuel takes place in front of the rotor of the supercharger, the temperature of the air drawn into the supercharger is decreased and the operating safety and independence upon the position of the aircraft is increased, so that this device is particularly suitable for aircraft performing acrobatics.

Illustrative embodiments of this invention are shown by way of example in the accompanying drawing, where Fig. 1 is a longitudinal sectional view of an atomizer with nozzles, Fig. 2 is a similar view of an atomizer with nozzles and a pan shaped disc for atomization, and Fig. 3 is a similar view of a detail of a modified pan-shaped disc provided with an additional blower for the supply of air.

Referring to Fig. 1, it will be seen that a centrifugal atomizer embodying the invention comprises a body 1 provided with a cavity 4, from which a number of substantially radial channels 2 open outwardly so that, during rotation of the body 1, centrifugal force drives the fuel mixture along channels 2 and the latter act as a centrifugal pump. In the embodiment according to Fig. 1 there are three rows of channels 2, and each channel is provided near its outer extremity with a nozzle 3 imparting a whirling movement to the mixture and with a small adjacent chamber 10 terminating in a discharge opening 11. A gap 12 for passage of a supply of air is

2

left between a fuel supply tube 5 and the body 1, with the tube 5 terminating in the neighbourhood of the row of channels 2 disposed closest to the inner end of the cavity 4. Shoulders 15 are provided within the cavity 4 for partly separating the inner ends of the channels 2 of the several rows. The body 1 is intended to be attached to the rotor of the engine supercharger.

In the embodiment of Fig. 2, the cavity 4a within the body 1a is provided with a radial partition wall 14 dividing this space into two parts, one of which serves for the supply of fuel, and the other for the supply of air. The space for the supply of fuel is provided with a row of channels 2a with nozzles 3a at their outer ends and further with channels 6 opening outwardly into an annular space between the body 1a and a pan shaped disc 7 having a cone-shaped inner surface and being attached to the body 1a. Radial channels 13 extend outwardly from the other space, that is, from the space in front of wall 14, and open into the same annular space between body 1a and disc 7 to supply air to that annular space.

In place of the channels 13, a ring of special blades 9 may be provided in the pan shaped disc 7 to provide a blower for sucking air into the annular space between the body and disc 7, as in Fig. 3.

The body 1a of the centrifugal atomizer of Fig. 2 is supported by the shaft of the rotor 8 of the engine supercharger, with which it is coaxial.

The centrifugal force transmits to the fuel passing through the channels 2 the energy required for atomization. The fuel is driven from the channels 2 into the nozzles 3 which impart a whirling movement to the mixture, and the latter passes the chamber 10 and is atomized when leaving the discharge opening 11. When the rate at which the fuel is supplied increases and the channels 30 2 of the innermost row are no more able to pass this increased rate of feed, the fuel passes over the shoulder 15 to the adjacent row of channels. This arrangement permits the selection of suitable cross sections for the nozzles in accordance with the required amount of atomized fuel. The attainment of perfect atomization is assisted by the air sucked through the space 12.

In the arrangement of Fig. 2, the part of the fuel passing through channels 2a is atomized by nozzles 3, for example, during operation at slow engine speeds, and the remaining fuel passing through channels 6 is atomized at the edge of the rotated pan shaped disc 7.

The atomizing by the pan shaped disc 7 is achieved by the fuel being thrown by centrifugal force from channels 6 against the conical inner wall surface of disc 7, whereupon the fuel proceeds in the direction of the increasing radius, and hence increasing centrifugal force, to the edge of the disc 7, whereby the thickness of the fuel film steadily decreases until it forms, on the edge of the disc, a narrow film which disperses into a fine mist. The air supplied either through the channels 13 or by the small blower blades 9 arranged in the disc 7 assists in the atomization of the fuel delivered through channels 6. It is apparent that the elements described with reference to Figs. 1, 2 or 3 may be combined.

60 The centrifugal atomizer according to this invention is primarily suitable for piston-type internal combustion engines and particularly for aircraft engines provided with superchargers.

What I claim is:

65 1. In an internal combustion engine with a supercharger having a rotated rotor; an atomizer for liquid fuel comprising a rotating body attached to the rotor of the supercharger and having an internal cavity opening axially in the direction away from the rotor, a fuel supply tube extending axially into said cavity through the opening of the latter, said body further having a plurality of

axially spaced rows of substantially radial channels opening outwardly from said cavity, the channels of at least the one of said rows closest to the rotor having nozzles adjacent their outer ends operative to impart a whirling movement to the fuel driven along the related channels by centrifugal force, each channel provided with a nozzle further having a small chamber into which the nozzle opens and a discharge opening communicating said chamber with the space outside of said body, and said fuel supply tube being spaced radially from the surface of said cavity to define an annular space therebetween forming at least part of means supplying air for admixture with the fuel supplied by said tube.

2. An atomizer as in claim 1; wherein said fuel supply tube terminates adjacent said one row of the channels and all of the latter have said nozzles; and wherein said surface of the cavity has radially inward directed shoulders partly obstructing said annular space at locations between the successive rows of channels so that the fuel issuing from said supply tube is initially discharged, along with air from said annular space, through the channels of said one row until the rate of fuel supply exceeds the flow capacity of the channels of said one row, whereupon the excess fuel backs-up past the shoulder between said one row and the next adjacent row for discharge, along with air from said annular space, through the channels of said next adjacent row.

3. An atomizer as in claim 1; further comprising a radial partition wall extending between said surface of the cavity and said fuel supply tube at a location intermediate the opposite ends of said cavity to divide the latter into an inner compartment with which said channels and fuel supply tube communicate and an outer compartment receiving the supply of air, said body having at least one additional row of radial channels extending from said outer compartment and opening at the outer surface of the body for the discharge of air, and a pan-shaped disc secured to said body and having a conical inner surface extending around, and spaced radially from a portion of the outer surface of the body and increasing

5 in diameter in the axial direction toward the supercharger rotor so that air discharged from said additional row of channels is deflected by said inner surface in the axial direction toward the rotor for mixing with the fuel issuing from the first mentioned rows of channels.

10 4. An atomizer as in claim 1; further comprising a pan-shaped disc secured to said body and having a conical inner surface extending around, and spaced radially from a portion of the outer surface of the body, with said conical inner surface of the disc increasing in diameter in the axial direction toward the rotor so that fuel being discharged from at least some of said channels impinges against said inner surface of the disc and travels axially along said inner surface for release, as a fine mist, at the relatively large diameter edge thereof; and wherein said means supplying air for admixture with the fuel discharges the supplied air between said outer surface of the body and said inner surface of the pan-shaped disc.

15 5. An atomizer as in claim 4; wherein said means supplying air includes a radial partition wall extending between said tube and said surface of the cavity to divide the latter into an inner compartment with which said channels and fuel supply tube communicate and an outer compartment receiving a supply of air, and an additional row of radial channels in said body extending from said outer compartment and opening at said portion of the outer surface of said body so that air discharged radially through said additional channels is deflected by said inner surface of the disc in the axial direction toward said edge of the disc.

20 6. An atomizer as in claim 4; wherein said means supplying air further includes a circular row of blades on said pan-shaped disc forming an air blower discharging between said outer surface of the body and said inner surface of the disc.
